UNITED STATES PATENT OFFICE.

WILLIAM W. DEAN, OF CHICAGO, ILLINOIS, ASSIGNOR TO KELLOGG SWITCHBOARD & SUPPLY COMPANY, OF CHICAGO, ILLINOIS, A CORPORATION OF ILLINOIS.

SUPERVISORY SYSTEM FOR TELEPHONE-LINES.

1,145,976.

Specification of Letters Patent. Patented July 13, 1915.

Application filed June 15, 1903. Serial No. 161,532.

To all whom it may concern:

Be it known that I, WILLIAM W. DEAN, a citizen of the United States of America, and resident of Chicago, county of Cook, 5 State of Illinois, have invented a new and useful Improvement in Supervisory Systems for Telephone-Lines, of which the following is a specification.

My invention relates to improvements in 10 telephone systems, more particularly in supervisory apparatus, my object being to provide an apparatus which is simpler than that ordinarily employed to accomplish the same results. My supervisory system is 15 particularly applicable to what is commonly termed two wire systems, that is, systems employing only two wires in the switchboard section of the line and two strands in the cord circuit, and at the same 20 time a common source of current at the central office furnishes current to the substations for talking purposes.

My invention operates upon what may be termed a marginal system. That is the initial 25 operation of the device is controlled by certain resistances and the further operation of the same is caused by a reduction of said resistances or by an increased flow of current through the coils of said device. In 30 the supervisory apparatus for instance, the insertion of the plug in an idle line operates the device far enough to cause the associated supervisory signal to be operated and the reponse of the called subscriber or the completion 35 of the line circuit to current there-over causes the further operation of the device to efface said signal.

In the accompanying drawing, which illustrates the invention, Figure 1 is a diagram 40 of a system embodying one form of my improvements, and Fig. 2 is a diagram of a modification.

In Fig. 1, L and L² represent subscribers' lines extending in two limbs 2 and 3 from 45 the respective substations to the central office. At the substation a call bell 4 and condenser 5 are placed in a bridge of the line conductors, while a transmitter 6 and receiver 7 are located in a bridge normally 50 open at the switch-hook 8. This substation apparatus is intended merely to typify any usual or desired common battery outfit. At the central office the line is fitted with the usual answering and multiple jacks J, J² and J³, and with the line signal 55 S the local circuit of which is controlled by the line relay R, located in the extension 9 of the line conductor 3 leading to the live pole of a battery B that is preferably common to all of the cord circuits of the exchange and a large number of telephone lines. A cut-off relay R² has its winding legged to ground from the sleeve conductor of the switchboard section of the line while the two movable contacts of said relay are 60 adapted to disconnect from their normal connections and complete the circuit of the line conductors 2 and 3 to the corresponding contacts of the jacks. Each operator is provided with a number of cord circuits 65 one only being shown, each including an answering plug P and a calling plug P² having tip and sleeve contacts adapted to register with the corresponding contacts of the jacks of the lines. The tip contacts of 70 these plugs are connected by flexible strands t and t² and the interposed condenser c, while the sleeve contacts are joined by the strands s and s² and the interposed condenser c². The battery B is bridged across 75 the answering end of the cord circuit and includes upon the tip side thereof the impedance coil 10 and upon the other side the supervisory relay r. This relay is provided with a movable contact 11 which is 80 actuated upon by a weight 12 or other suitable device and carries a preferably adjustable contact 13. This latter contact is adapted to engage with a contact mounted upon the pivoted arm 14 which is also provided with 85 a weight such as 15 or other suitable device; and a second contact carried by said arm is adapted normally to engage the adjustable stationary contact 16, the latter being joined to the grounded pole of the battery B by a 90 suitable conductor 17 while the armature 11 of said relay r is connected by conductor 18 with the live pole of said battery and includes a suitable supervisory signal S² preferably in the form of a small incandescent lamp. The resistance through which the 95 said relay r is intended to operate is such that the armature 11 is first attracted until it engages the movable contact 14 but is not sufficiently energized at this stage of the 100 operation to press said movable contact 14

away from the stationary contact 16. It is therefore seen that the local circuit of the supervisory lamp S^2 is at this time completed; but upon a further flow of current 5 through the relay r which will occur as hereinafter pointed out, the armature 11 is attracted with sufficient force to move the lever 14 away from the stationary contact 16 to thereby open the circuit of the lamp S^2 which is accordingly extinguished.

Across the calling end of the cord circuit a battery B^2 is connected through the impedance coil 19 and the relay r^2 corresponding to the relay r upon the other side of the cord circuit, said latter relay controlling through similar devices the local circuit of the supervisory lamp S^3 .

The operator's receiver 20, the secondary of her induction coil 21 and the condenser 20 c^3 are adapted to be bridged across the calling end of the cord circuit in the usual manner while the transmitter 22 is fed from battery in the ordinary manner. A calling generator 23 is adapted to be connected with 25 the tip side of the cord circuit by the operation of the tip ringing spring 24, while the sleeve side of the cord is simultaneously connected through a branch conductor 25 and a suitable resistance 26 directly with the battery B^2 .

In the operation of this form of the invention a subscriber calls in the usual manner by taking up his receiver thereby completing a path for current over his metallic line and 35 operating his line signal S . Upon observing the signal the operator inserts the answering plug P of the cord circuit thereby completing a path for current from the live pole of the battery B , through the relay r , strand s 40 of the cord circuit and the sleeve conductor of the jack section of the line and the winding of the cut-off relay R^2 to ground. The current in this path is sufficient to operate said cut-off relay to disconnect the line conductors from their normal contacts thereby extinguishing the line signal and to connect them with the switchboard section of the line to thereby place the line in condition for conversation. The current in this path is 45 also sufficient to operate the supervisory relay r to cause it to close its contact 13 against the lever 14 and only sufficient for this purpose if the subscriber's telephone were not in use whereby the supervisory signal S^2 would be operated; but owing to the 55 fact that the subscriber's telephone is in use, the path for current is completed over the telephone line and through the tip strand of the cord circuit to the other pole of the battery. The line circuit being in parallel 60 with that of the cut-off relay R^2 causes a sufficient reduction in resistance to the passage of current through the relay r to cause an increased current flow therethrough 65 thereby completely operating it to open the

local circuit of said signal at the contact 16. This signal is accordingly inert at this stage of the connection.

Upon connecting her telephone with the line and learning the order for the connection the operator proceeds to test the condition of the wanted line. If idle, the test contacts of the lines are connected with ground through the cut-off relay and since the tip of the testing plug is likewise 75 grounded no flow of current takes place and no click is received. Assuming that the line is busy, however, the said test rings are connected with either the battery B or B^2 and the application thereto of the grounded tip 80 of the testing plug results in a flow of current over the strand t^2 of the testing cord and a click is received in the operator's receiver to indicate to her that the line is busy.

Assuming that the line is found idle, the 85 calling plug P^2 is inserted in the jack of the line and the ringing generator operated. The cut-off relay is maintained operated during ringing by current from the battery B^2 over conductor 25 even though the sleeve 90 strand is severed by the sleeve spring of the ringing key 24. After calling the subscriber and before his response current from the battery B^2 is flowing through the supervisory relay r^2 over the strand s^2 and 95 through the cut-off relay R^2 of the called line. The resistance of the supervisory relay r^2 is so proportioned that it will merely close contact 13 but will not move arm 14 away from contact 16. This adjustment is readily 100 obtained for the reason that only constant resistances are encountered. For example, the resistance of the cut-off relay R^2 is constant, the resistance of circuit for any line is 105 constant, so that the desired operation of the supervisory relay r^2 may be readily obtained. The local circuit of the supervisory lamp S^3 is therefore closed and the lamp lighted to indicate to the operator that the 110 subscriber has not yet responded. As soon as he responds, however, current from the battery B^2 circulates over the metallic line, and causes a considerably increased flow of current over the strand s^2 of the cord circuit 115 and through the supervisory relay r^2 . The said relay r^2 is further adjusted to respond to this increased current and therefore moves contact 14 away from contact 16, to open the local circuit of the supervisory signal S^3 thereby extinguishing it.

During conversation current is flowing from the batteries B and B^2 over the telephone lines, the voice currents being prevented from short circuiting across the cord 125 circuit by means of impedance coils 10 and 19 and the relays r and r^2 and being repeated from one line to the other by the condensers c and c^2 . At the termination of the conversation the return of the subscribers' 130

receivers to their hooks serves to decrease the flow of current through the supervisory relays r and r^2 which accordingly allow the movable contacts 14 to close against the stationary contacts 16 thereby again closing the local circuits of the supervisory lamps S^2 and S^3 which are lighted to indicate to the operator the termination of the conversation. Upon observing these signals she withdraws 10 the plugs from the jacks of the telephone lines thus restoring all parts to normal condition.

In Fig. 2 the margin of operation of said supervisory relays r and r^2 is increased. 15 This is accomplished by dispensing with the impedance coils 10 and 19 of Fig. 1 and putting extra coils upon the cores of said magnets r and r^2 , these being indicated at 27 and 28. When, therefore, the telephone at the subscriber's station is removed from the hook the current flowing to the grounded pole of the battery passes first through the said additional coils 27 and 28. This effect is added to that of increasing the current flow through the 20 other coils as described with reference to Fig. 1, since it is apparent that the same increased flow of current now results as before and that the sleeve windings of said relays are effected in the same manner. This latter 25 arrangement tends to render the action of said relays more positive.

I claim:—

1. In a telephone system, the combination with a telephone line, of a cord circuit to 35 establish connections with the line for conversation, a line signal, a cut-off relay for the line adapted to render the line signal inoperative when a connection is established, a supervisory relay associated with the cord 40 circuit, means for establishing a path for current through said supervisory and cut-off relays when a connection is established with the line to simultaneously operate the cut-off relay and to partially operate the 45 supervisory relay, a supervisory signal having its circuit closed during such period of partial operation of the supervisory relay, and means whereby when the subscriber's telephone is in use an increased flow of 50 current through said supervisory relay completely operates the same and thereby renders the supervisory signal inoperative, substantially as described.

2. In a telephone system, the combination 55 with a telephone line, of a cord circuit to establish connections for conversation therewith, a supervisory relay associated with the cord circuit, a central source of current to furnish current over the telephone line for 60 conversation, said relay being partially operated during the connection when the subscriber's telephone is not in use to operate the supervisory signal, and an additional winding upon said relay in the path of current over the telephone line when the tele-

phone is in use, said additional winding assisting in the complete energization and operation of said relay to render the supervisory signal inoperative, substantially as described. 70

3. In a telephone system, the combination with a telephone line, of a cord circuit to establish connections with the line for conversation, a line signal, a cut-off device for the line adapted when operated to render 75 the line signal inoperative, a supervisory signal controlling magnet associated with the cord circuit, a suitable signal adapted to be controlled thereby, means for establishing a path for current through said 80 magnet and said cut-off device when a connection is established with the line for conversation, the current in said path when the subscriber's telephone is upon its hook being only sufficient to simultaneously operate the cut-off device to efface the line signal and said magnet in such manner as to cause the latter to disclose its signal, and means whereby when the subscriber's telephone is in use a low resistance path is provided 85 for current through said magnet which is more completely energized thereby and serves in this condition to efface the supervisory signal, substantially as described. 90

4. In a telephone exchange system, the combination of a subscriber's line free from operative earth connections outside of the exchange, a link conductor associated therewith, a non-polarized electromagnet, a normally effaced 100 supervisory signal and a source of current all associated with said link conductor, a path under the control of the operator for causing a flow of current through said magnet to cause the display of said signal, a branch path for current directly controlled by the subscriber when said link conductor is connected with said line and means for closing both branches contemporaneously to cause the effacement of said signal by increasing the energization of the said magnet, substantially as described. 105

5. A telephone system comprising telephone lines, cord circuits for interconnecting said lines, supervisory relays for the cord circuit, means responsive to connection of a cord circuit with an idle called line to establish an energizing circuit for the supervisory relay whereby it is partly operated to display a signal, a second winding for the supervisory relay, and means for establishing an energizing circuit through the second winding upon response from the called subscriber to effect an increased energization of the supervisory relay for effacing the signal. 110

6. A telephone system comprising telephone lines having line jacks and cut-off relays, cord circuits for interconnecting said lines, supervisory relays for the cord circuit, a source of current, means responsive 115

to connection of a cord circuit with an idle called line to establish a circuit for the supervisory and cut-off relays whereby the cut-off relay is operated and the supervisory 5 relay is partly energized to display a signal, and means for establishing an additional energizing circuit for the supervisory relay upon response from the called substation and maintaining the initial and additional 10 circuits to effect an increased energization of the supervisory relay for effacing the signal.

7. A telephone system comprising telephone lines having cut-off relays, cord circuits for interconnecting said lines and having supervisory relays, a source of current having one of its poles connected to a terminal of the supervisory relay and its other pole connected to a terminal of the cut-off 15 relay, means responsive to connection of a cord circuit to a telephone line to connect a supervisory and a cut-off relay in series whereby said cut-off relay is operated and the supervisory relay partly operated to display a signal, and means at the connected 20 substation for establishing and maintaining 25

an energizing circuit in addition to the initial energizing circuit for the supervisory relay to increase its magnetization and effect a further operation thereof to efface the 30 signal.

8. A telephone system comprising telephone lines, cord circuits for interconnecting said lines, supervisory relays for the cord circuit, means responsive to connection of a cord circuit with a telephone line to establish an energizing circuit for the associated supervisory relay whereby it is partly energized to display a signal, and means controlled at the connected substation for adding to the first energizing circuit of the supervisory relay in its initial direction to cause an increased energization and magnetization of the supervisory relay to effect a further operation thereof for effacing the 35 40 45 signal.

Signed by me at Chicago, county of Cook, State of Illinois, this 12th day of June, 1903.

WILLIAM W. DEAN.
